No. 853,991.

PATENTED MAY 21, 1907.

W. H. McKEIVER.
DOOR OR SASH LOCK.
APPLICATION FILED SEPT. 10, 1906.

UNITED STATES PATENT OFFICE.

WILLIAM H. McKEIVER, OF INDIANAPOLIS, INDIANA, ASSIGNOR TO THOMAS M. HARDY, JR., OF PENDLETON, OHIO.

DOOR OR SASH LOCK.

No. 853,991.

Specification of Letters Patent.

Patented May 21, 1907.

Application filed September 10, 1906. Serial No. 333,959.

To all whom it may concern:

Be it known that I, WILLIAM H. McKEIVER, a citizen of the United States, residing at Indianapolis, in the county of Marion and State of Indiana, have invented certain new and useful Improvements in Door or Sash Locks, of which the following is a specification.

The object of my invention is to produce a small and convenient device by means of which any door, window-sash, or similar moving part may be easily locked, the construction being such that it may be readily operated, and such that it itself may be readily held against all possible improper movement.

The accompanying drawings illustrate my invention;

Figure 1 is a perspective view of my improved lock in connection with adjacent portions of a door and door casing; Fig. 2 a similar view with the door open; Fig. 3 a perspective view of my device showing the side opposite to that shown in Fig. 1; Fig. 4 an elevation in partial vertical section; Fig. 5 a section on line 5—5 of Fig. 4; and Fig. 6 a detail showing the positions of the parts when held against improper movement.

In the drawings, 10 indicates a thin main body adapted to be inserted between the two parts to be locked, said body at its thin end being provided with suitable screw holes 11 by which it may be permanently attached to one of the parts to be locked, if desired, and also provided upon one face with a sharp spud 12 which may be temporarily forced into the door casing or a window-sash.

At the outer end of body 10 I provide a pair of ears 13 and 14 which are vertically perforated to receive a threaded shank of the screw 15, said shank passing freely through the perforations of the ears and being axially reciprocable therethrough. Threaded upon screw 15, between the two ears 13 and 14, is a locking head 16, that portion of the head lying between the two ears being considerably thinner than the distance between the ears so that it may be vertically reciprocated between said ears. This locking head 16 is provided with a face 16', parallel with the axis of screw 15, which face is adapted to engage the inner face of the door 17. Head 16 is provided at its lower inner corner with an upwardly projecting finger 16" which lies

a sufficient distance from the main body of head 16 to form a vertical notch 16''' adapted 55 to receive the main body 10.

Arranged in ear 14, under the end of screw 15, is a spring 18 which normally urges the screw 15 axially upward so that the head 15' thereof lies a distance from the upper face of 60 ear 13 equal to or greater than the vertical depth of the notch 16'''.

The operation is as follows:—The thin shank of body 10 is inserted between a door 17 and a casing 20, either by forming a recess 65 in the face of the casing for permanent attachment, or by slipping the shank between the door and casing and forcing the door shut, the spud 12 in this case preventing any withdrawal. The door being shut, head 16 70 is then swung around from the position shown in Fig. 2 to the position shown in Fig. 1, and screw 15 is forced downward against the action of spring 18 until finger 16" can be swung beneath the thin projecting portion of body 75 10, whereupon the face 16' is in engagement with the door, and when the screw 15 is released the head 16 moves upward so that body 10 lies in the notch 16''', thus preventing any accidental displacement of head 16. 80 If it be desired to lock head 16 against displacement, the operator has merely to turn screw 15 in head 16, whereupon the head 15' of the screw moves down against the upper face of ear 13 and thus prevents any longitudinal movement of the screw, and consequently 85 any movement of head 16 to withdraw finger 16" from engagement with body 10.

I claim as my invention;

In a device of the class described, the combination, with the main body having a portion adapted to be inserted between two members to be locked, of a screw axially movable within said main body, a locking head threaded on said screw, and means carried by the locking head for engagement with the main body by relative movement axially of the screw. 95

In witness whereof, I, have hereunto set my hand and seal at Indianapolis, Indiana, 100 this 1st day of September, A. D. one thousand nine hundred and six.

WILLIAM H. McKEIVER. [L. S.]

Witnesses:

ARTHUR M. HOOD,
THOMAS W. McMEANS.
